UNITED STATES PATENT OFFICE

FREDERICK H. KNAPP, OF KELSO, WASHINGTON

CABLE CLAMP

Application filed November 5, 1928. Serial No. 317,319.

My invention relates to rope clamps, consisting of primary and secondary elements. Means being provided for adapting the same to a wire rope between its extreme ends.

5 My invention consists of a primary slotted sleeve having a spiral fluted inner surface, the said sleeve being threaded on its outer surface. The secondary element consists of a sleeve having a tapered threaded bore, which 10 communicates with the outer threaded surface of the primary element, allowing the primary element to conform with the taper bore of the secondary element, and in this manner contracting the primary element about the 15 rope.

The prime object of my invention is to provide a cable clamp for logging equipment, where one line or wire rope is to be joined to another line between its extreme ends.

20 A further object of my invention is to provide a cable clamp that can be applied to the wire rope at any desired point without releasing said wire rope from its work.

A further object of my invention is to provide 25 a cable clamp that can be used on the line without damaging the line, and can be easily attached to the line, or removed from the same.

A further object of my device is to provide 30 a cable clamp that will firmly grip the cable, without separating the strands or kinking the cable.

A further object of my device is to provide 35 a cable clamp having a spiral fluted inner surface to correspond with the spiral twist in the wire rope.

A still further object of my invention is to provide 40 a cable clamp that will pass through the cable block without damaging the block, cable, or clamp.

With these and incidental objects in view, the invention consists in certain novel features of construction and combination of parts, the essential elements of which are set forth in the appended claims, and a preferred form of embodiment of which is hereinafter described with reference to the drawings which accompany and form a part of this specification.

In the drawings:
50 Fig. 1 is an assembled side view of my in-

vention in place upon a wire rope, in this case the main haul line, having the slack pulling line positioned thereon.

Fig. 2 is a perspective view of the slotted primary element. 55

Fig. 3 is a perspective view of the locking nut, or secondary element.

Fig. 4 is a partial cross sectional view of 60 my cable clamp about to be clamped to wire rope.

Fig. 5 is a cross section of the clamp after being clamped tight to rope.

Fig. 6 is a preferred form of wrench for locking clamp to rope.

Fig. 7 is a perspective view of another preferred form of clamp. 65

Fig. 8 is a perspective view of the split clamp being placed upon the cable.

Like reference characters refer to like parts throughout the several views. 70

It has been my experience that clamps heretofore separate, the strands of the cable, or kink or damage the same, when the clamp is removed. In my cable clamp a primary sleeve 1 and a secondary sleeve 2 is provided. 75 The bore of the primary sleeve 1, has taper spiral surface 3 which conforms to the twist of the cable 6, to insure a tight and even grip about the said cable, without kinking or damaging the cable. Slits 4 are cut length-wise of the sleeve 1. The slotted end of said sleeve has a larger bore than the opposite end. The secondary sleeve 2 has a tapered thread 7 cut on its inner surface which co-acts with the threaded outer surface 8 of the sleeve one. As sleeve 2 is threaded forward on sleeve 1, sleeve 1 is contracted tightly about the cable 6, shoulder 10 serves as an abutment for the end 9 of sleeve 2. Holes 11 are provided in sleeves 1 and 2 to accommodate the spanner wrench 12, to be used for tightening or loosening the clamp. 85

In Figs. 7 and 8, I have shown a clamp that can be applied to a cable without releasing 90 either end of the cable from its work. Sleeve 1 has a removable section 14, which can be removed from the body of sleeve 1, when placing the sleeve about the cable. The V shaped ribs 15 of the section 14 co-acts with 95

the V shaped groove 16, to hold the section 14 in alignment with the sleeve 1.

The sleeve 2 is U shaped in form having a hinged gate 17 journaled about pin 18 and latched by the pin 19 or vice versa. A latching bar 18A outwardly extends from the hinged gate 17 and the same is adapted for engagement between the locking lugs 19A when closed, in order that the locking pin 19 10 may be made to engage within the holes disposed within the respective elements when the holes become in registerable alignment with each other. The object of the hinged gate is to create an opening whereby the sleeve may be applied to the cable without releasing the ends of the said cable. The tongues 20 and 21 of the sleeve 2 engage the grooves 22 and 23 of gate 17, the object of which is to keep the sleeve 2 from spreading 15 when the same is threaded upon the sleeve element 1. A swivel eye 24 is provided for the receiving of the cable that is to be secured to the cable to which the clamp is applied.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, consisting of primary and secondary co-acting elements, the inner one of the co-acting elements having a slotted inner sleeve and a tapered and spirally fluted bore, threaded on its outer surface, said sleeve having a removable section, the other of the elements having a tapered bore, said member consisting of a U shaped element having a gate hinged at its opening, an eye disposed in said gate, means for applying the element to a rope without disturbing the secured end of the rope.

2. In a device of the class described, the combination of primary and secondary co-acting threaded elements, the primary element consisting of a sleeve having a tapered bore, said bore having its greatest diameter opposite its tapered end, spirals disposed within the inner surface of said sleeve, threads disposed upon the outer surface of said sleeve, longitudinal slits disposed within said sleeve, a portion of said sleeve being removable thereby permitting greater facility in the use of the device, said portion having ribs disposed at each end of its base, grooves disposed within the oppositely disposed edges of the remaining part of the sleeve in registerable alignment with the ribs, said ribs and grooves adapted for preventing movement of the removable portion when placed into position, and a secondary threaded element adapted to threadably engage the

primary element and inwardly contract the slotted sleeve.

3. In a device of the class described, the combination of primary and secondary co-acting threaded elements, the secondary element consisting of a U-shaped bored element, tongues disposed longitudinally of its edges, a gate hingedly secured to said U-shaped bored element, grooves disposed within the gate in registerable alignment with the tongues, said tongues and grooves adapted for preventing movement of the gate when in closed position, locking means disposed upon the gate and upon the U-shaped bored element, and a primary threaded element 70 75 80 adapted for being threadably engaged by the secondary element.

4. In a device of the class described, the combination of primary and secondary co-acting threaded elements, means disposed 85 within the primary element for enabling the primary element to adapt itself to the contour of a cable upon the application of pressure thereon, means disposed within the secondary element for enabling the secondary 90 element to intimately engage with and apply pressure upon the primary element, and means disposed within both the primary and secondary elements for permitting the removal of both or either of them from any 95 part of a cable.

5. In a device of the class described, the combination with a primary threaded element, a secondary element comprising a U-shaped bored body member, threads disposed within its inner portion, a gate hingedly secured to the body member, said gate having its inner portion threaded in registerable alignment with the threads disposed within the body member, a tongue longitudinally disposed at each edge of the body member, a groove longitudinally disposed at oppositely disposed edges of the gate and in registerable alignment with the tongues, locking lugs outwardly extending from the body member, and a latching bar disposed upon the gate in registerable alignment with the locking lugs.

6. In a device of the class described, in combination with a secondary threaded element, a primary element comprising a sleeve having a tapered bore, spirals disposed within the inner surface of the sleeve, threads disposed about its peripheral edge, slits disposed within the body of the sleeve, a portion of said sleeve being removable, ribs disposed at each end of the collar portion of said sleeve portion, and grooves disposed within the remaining portion of the sleeve in registerable alignment with the ribs.

FREDERICK H. KNAPP.
